(57) **CLAIM**

The ornamental design for a storage box, as shown and described.

DESCRIPTION

FIG. 1 is a front, top and right-side perspective view of a storage box showing a first embodiment of our new design; FIG. 2 is a front view thereof; FIG. 3 is a rear view thereof; FIG. 4 is a top view thereof; FIG. 5 is a bottom view thereof; FIG. 6 is a right-side view thereof; with the left-side view being a mirror image thereof; FIG. 7 is a front, top and right-side perspective view of the first embodiment of the storage box shown in an alternate configuration in a state of use; FIG. 8 is a front, top and right-side perspective view of the first embodiment of the storage box shown in another alternate configuration in a state of use; FIG. 9 is a front, top and right-side perspective view of the storage box showing a second embodiment of our new design; FIG. 10 is a front view thereof; FIG. 11 is a rear view thereof; FIG. 12 is a top view thereof; FIG. 13 is a bottom view thereof; FIG. 14 is a right-side view thereof; with the left-side view being a mirror image thereof; FIG. 15 is a front, top and right-side perspective view of the second embodiment of the storage box shown in an alternate configuration in a state of use; and, FIG. 16 is a front, top and right-side perspective view of the second embodiment of the storage box shown in an alternate configuration shown in another alternate configuration in a state of use.

(Continued)

The broken lines shown illustrate portions of the storage box that form no part of the claimed design.
